FUSE-MAKING MACHINE

Herbert Perry Renwick, Chicago, Ill., assignor to
Howard F. Leopold, Chicago, Ill.

Application September 17, 1934, Serial No. 744,341

5 Claims. (Cl. 113—1)

This invention relates to a fuse-making machine.

It is an object of this invention to provide an improved fuse-making machine which is relatively simple and inexpensive in construction and efficient in use.

Another object of the present invention is to provide a machine for making one unit of a fuse of the so-called cartridge type, to replace the manual method now in use for making these units.

A further object of the invention is to provide a machine for attaching the fuse strips of cartridge fuses to the caps of the same.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a side elevational view of a preferred form of the new fuse-making machine;

Fig. 2 is a fragmentary side elevational view;

Fig. 3 is an end elevational view of the new machine, partly in section;

Fig. 4 is a vertical sectional detail view on line 4—4 in Fig. 3;

Fig. 5 is a vertical sectional view on line 5—5 in Fig. 3;

Fig. 6 is a fragmentary sectional detail view;

Fig. 7 is a vertical sectional view on line 7—7 in Fig. 5;

Fig. 8 is a vertical sectional view on line 8—8 in Fig. 5;

Fig. 9 is a bottom plan view on line 9—9 in Fig. 5; and

Fig. 10 is a fragmentary top plan view on line 10—10 in Fig. 5.

Before proceeding with a detailed description of the construction and operation of the new machine a general description of the construction and operation of the same will be given, following which a detailed description of both the construction and operation of the new machine will be given, thus making the latter more intelligible.

A preferred form of the new machine is shown in the drawings, is therein generally indicated at 11, and comprises a supporting frame 12 upon which is mounted an endless carrier 13 of the chain type, the carrier 13 including a row or series of cylindrical carrier or receptacle tubes 14, each open at its upper end (Fig. 6). Adapted to be inserted onto the open upper end of each of these

tubes 14 (Fig. 2) in any suitable manner, as by means of a suitable machine or device, or manually if desired, is a cap 18; each of these caps 18 having an opening in the form of a hole or slit formed in the top wall thereof for the reception of a strip 22 of fuse wire, as will be explained more fully hereinafter; a suitable storage receptacle 28 for a supply of the caps 18 being arranged upon the supporting frame 12, (Fig. 1) so that if the feeding operation is done manually the operator of the machine may readily remove the caps from the receptacle 28 and place them upon the tubes 14; it being understood that this operation may be done by means of suitable mechanical or electrical means (not shown) if desired.

Fed toward the fuse cartridge caps 18 and carrier tubes 14 by web-feeding means, generally indicated at 15 and comprising a train of feed rolls, interconnected by means of suitable gearing, is a web of fuse wire 16 and when, during movement of the carrier 13, the tubes 14 successively come under, and into registration with, the web of fuse wire 16, the free end portion of the web 16 is inserted successively through the openings, holes or slits in the caps 18 into the carrier tubes 14 and after each of such insertions of the free end portion of the fuse wire web through the opening in the cap 18 in registration therewith into the corresponding carrier tube 14, a knife 17 (Fig. 6) is moved across the web 16 and severs a strip or portion 22 of the web 16 from the body or free end portion of the same; each strip 22 being severed long enough so that the upper end portion 26 thereof projects slightly out of the corresponding tube 14 through the opening or hole 19 in the cap 18 thereof (Fig. 6).

After each operation of inserting the free end portion of the fuse wire web 16 through the opening or hole in the cartridge fuse cap and into the corresponding carrier tube 14 in registration therewith, and after each operation of severing the thus inserted free end portion of the fuse wire web 16 from the body of the same, the free end portion of a web of fusible solder wire 23 is fed by a train of gear-interconnected feed rollers 24 into a position directly over and in registration with the opening in the cap 18 (of the loaded tube 14) and above the projecting portion 26 of the fuse strip 22, (Fig. 6); and at this time the hot tip 20 of a soldering iron 21, of any suitable design or type, but preferably of the electrically heated type, is automatically moved down into engagement with the free end portion of the web of solder metal 23, thereby fusing the free end portion of the solder web 23 and depositing a

fused globule or small mass of solder 25 (Fig. 6) onto the cap 18 over the opening or hole therein, thus fusing the projecting upper end portion 26 of the strip of fuse wire 23 and the small mass of solder 25 to the cap 18 and thereby closing the opening or hole 19 in the cap 18.

As the carrier 13 continues to move, in a step by step movement, (right to left, Fig. 6) the cartridge caps 18, with their attached strips 22 of fuse wire soldered thereto, engage a stripper 78 and are withdrawn by the latter out of the carrier tubes 14, whereupon they are dumped (Fig. 1) by gravity out of the open-ended carrier tubes 14 and off the carriage or carrier 13 into a suitable receptacle 27 provided therefor upon the supporting frame 12 of the new machine 11; thus completing the operation of the machine. Thereafter the caps 18 and attached fuse strips 22 may be assembled, in any suitable manner and by either mechanical means, (not shown) or manually, into a complete fuse of the cartridge type.

Having thus given a general description of the construction and operation of the new machine 11, so as to render that which is to follow more intelligible, a detailed description of the construction of the same will now be given, followed by a detailed description of the operation thereof.

The moving parts of the new machine 11 may be operated by any suitable prime mover, such as, for example, the electric motor 29; power from the latter being transmitted by an endless power-transmitting element in the form of a belt 30 to a pulley or sheave 31 which is arranged upon a shaft 32; the shaft 32 being rotatably journaled in the frame 12 and carrying a beveled gear 33 which meshes with a beveled gear 34, the latter being mounted on a shaft 35 (Fig. 9). Power is transmitted from the shaft 35 through a speed-reducing gear train 36 (Fig. 9) to the main operating shaft 37 of the machine, and associated with the shaft 37 is a clutch 38 which may be operated at will by a clutch control lever 39.

Power is transmitted from the main operating shaft 37 to the endless carrier 13 as follows: Arranged on the shaft 37 is a disc 40 which has a laterally extending pin 41 (Fig. 9) and this pin 41 engages with a so-called Geneva gear 42, the latter being arranged upon a shaft 43. The shaft 43 carries a beveled gear 44 and the latter meshes with a corresponding beveled gear 45 which is arranged on a vertical shaft 46 (Fig. 3). At its upper end the shaft 46 carried a beveled gear 47 which meshes with a corresponding beveled gear 48, the gear 48 being mounted on a shaft 49 (Fig. 5) which carries a sprocket 50, (Figs. 3 and 6). The endless carrier or chain 13 revolves around the sprocket 50 and around a corresponding sprocket 51 which is mounted on a shaft 52, (Fig. 5), the carrier 13 and the carrier tubes 14 being advanced in a step by step motion, (right to left, Fig. 5), by the pin 41 and Geneva gear 42, sprockets 50 and 51, shafts 49 and 52, and associated parts.

During the operation of inserting the free end portion of the fuse wire web through the openings 19 in the cartridge caps 18 and into the carrier tubes 14, the carrier tubes 14 are held in a vise or clamp 53 (Fig. 7). This clamp 53 comprises a stationary jaw element 54 and a pivotally mounted or movable jaw element 55, the movable jaw element 55 having attached thereto a laterally projecting arm 56 (Fig. 7). This pivotal jaw element 55 of the clamp or vise 53 is moved into and out of clamping engagement with the stationary jaw element 54, so as to hold the car-

rier tubes 14 and the openings 19 in the cartridge fuse caps 18 one at a time, that is, successively, in registration with the free end portion of the web of fuse wire 16, as the carriage 13 is moved, in a step by step movement, (right to left, Figs. 1 and 6); this movement of the pivotal jaw element 55 being effected by the arm 56 through the instrumentality of a push rod 57 which, in turn, is operated by a rocker arm 58 (Fig. 7); the rocker arm 58 being mounted on a rock shaft 59 and having a roller 60 which rides one cam surface 79 of a cam 61 which is mounted on the shaft 37, whereby as the shaft 37 and cam 61 are revolved by the motor 29, the movable jaw 55 of the vise or clamp 53 is alternately moved into and out of clamping engagement with the stationary jaw 54 of the vise or clamp 53, by operation of the cam 61, and its cam surface 79, roller 60, rocker arm 58, push rod 57 and arm 56.

The cam 61 likewise includes a second cam surface 80 (Figs. 5, 7 and 9) and this cam surface 80 operates or advances the free end portion of the web of fuse wire 16, through the instrumentality of a rocker arm 67, which is mounted on a shaft 85, and carries a cam roller 94 which 25 rides a cam surface 80 of the cam 61; a push rod 64 being operated against a resetting spring 100 by the rocker arm 67 (Figs. 4 and 7) and having engagement at its upper end with an arm 81 of the feed roll 82 which carries the fuse wire 30 web 16 (Fig. 4).

A similar arrangement is provided for feeding the free end portion of the web of solder wire 23, in a step by step movement, under the hot point or tip 20 of the soldering iron 21. This arrangement comprises a cam 62 which is arranged upon the shaft 37 adjacent the cam 61 (Figs. 5 and 8). This cam 62 includes a cam surface 83 upon which rides a cam roller 95 which is carried by a rocker arm 63; the rocker arm 63 being mounted on the 35 shaft 59 and operating a push rod 68 against a resetting spring 99, the push rod 68 engages at its upper end an arm 84 of the feed roll 74 which carries the web 23 of solder wire (Figs. 7 and 8).

The soldering iron 21 is pivotally mounted between its ends, as at 75 (Fig. 1) on a support 76 and is urged by a spring 89 in a direction (clockwise, Fig. 6) to dispose its hot tip 20 upon the free end portion of the web of solder wire 23 (Fig. 6); the soldering iron being normally held out of engagement with the free end portion of the web of solder wire 23 by a push rod 73; the upper end portion of the push rod 73 engaging with an arm 77 of a carriage 72 which supports the soldering iron 21 (Fig. 4) and normally holding the tip 20 of the soldering iron out of engagement with the web of solder wire 23 (Fig. 4) against the action of the spring 89; while the lower end portion of the push rod 73 engages with a rocker arm 87 (Fig. 8) which carries a cam roller 93 60 which, in turn, rides a cam surface 86.

Likewise provided on the cam 62 is a lug 78 (Fig. 8) which operates a member 69, the member 69 being pivotally mounted between its ends, as at 70, on the supporting frame of the machine. This member 69 operates the knife 17, against the action of its resetting spring 96 (Fig. 10) and the knife 17 severs the free end portion of the web of fuse wire 16 at regular intervals after each operation of inserting the free end portion of the web through the opening in the cap 18 and into the corresponding carrier tube 14.

Mounted on the frame 12 adjacent the web-severing knife 17 is a web-straightening device 97 (Fig. 6) which bears against the free end por- 75

tion of the fuse wire web 16 and straightens the latter out as it passes into the guide 98.

A switch 88 controls the motor 29 and the electrical heating element in the soldering iron 21, (Fig. 3) is connected by a conductor 91 to an outlet box 92.

Operation

The machine is set in operation by attaching the conductor 91 to the outlet 92 and closing the switch 88, thereby closing circuit to the motor 29. The motor 29 being thus set in operation, power is then transmitted to the carrier 13 by way of the belt 30, pulley 31, shaft 32, gears 33-34, (Fig. 9) shaft 35, speed reducing gear train 36, clutch 38, disc 40, pin 41, Geneva gear 42, shaft 43, gears 44 and 45 (Fig. 3), shaft 46, gears 47 and 48, shaft 49, (Fig. 6) and sprocket 50, whereupon the carrier 13 is moved, in a step by step movement, (right to left, Figs. 1, 5 and 6) every time the pin 41 on the disc 40 engages in one of the notches in the Geneva gear 42 (Figs. 3 and 9).

The carrier 13 being thus set in motion, the cartridge fuse caps 18 are removed from the storage receptacle 28 (Figs. 1 and 2), in any suitable manner, as by means of a suitable mechanical device (not shown) or manually, if desired, and are placed upon the open upper ends of the fuse strip receptacle tubes or carriers 14 which are mounted on the carrier 13 and spaced at intervals therealong.

As the fuse strip receptacle or carrier tubes 14 are moved one at a time into registration with the free end portion of the web of fuse wire 16 (Fig. 6), the cam surface 79 of the cam 61 (Fig. 5) which is then revolving with its supporting shaft 37 (the main operating shaft) acts through the rocker arm 58-60 to raise a shoulder on the push rod 57 (Fig. 7) against the arm 56 of the movable clamping jaw 55 and against the action of the spring 90 and thereby pivots the movable clamping jaw 55 of the vise or clamp 53 into closed position so as to hold the fuse receptacle tube 14 and the opening or hole in the cap 18 arranged thereon (Fig. 6) momentarily in registration with the lower and free end portion of the fuse wire web 16, during the operations of inserting the free end portion of the fuse wire web 16 through the opening or hole 19 in the cartridge fuse cap 18 arranged thereon and into the corresponding carrier tube and severing the thus inserted free end portion of the web 16 from the body of the same.

At this time the cam surface 80 of the cam 61 (Fig. 5) acts through the cam roller 94 and the rocker arm 61 (Fig. 7) to raise the push rod 64 against the action of the resetting spring 100 (Figs. 4 and 7), whereupon a shoulder on the upper end portion of the push rod 64 engages the arm 81 of the fuse wire feed roll 82 (Fig. 4) and thereby rotates the latter (clockwise, Fig. 4). This operation advances the free end portion of the fuse wire web 16 past the web-severing knife 17 and through the opening or hole 19 in the cartridge cap 18 into the fuse wire receptacle or carrier tube 14 (Fig. 6); whereupon the lug 78 on the cam 62 (Figs. 4 and 8) engages the pivotal member 69 and rocks the latter (clockwise, Fig. 4) at 70, thus causing the upper end portion of the rockable member 69 to engage the web-severing knife 17 and pivot the latter (left to right, Fig. 6) against the action of its resetting spring 96 into engagement with the fuse wire web 16.

In the foregoing manner the lower and free end portion of the fuse wire web 16 is inserted

through the opening or hole 19 in the cap 18 into the fuse wire receptacle or carrier tube 14 and severed from the body of the web 16.

At this interval the roller 60 carried by the rocker arm 58 rides off the cam surface 79 of 5 the cam 61 whereupon a spring 90 acts through the push rod 57 and the arm 56 to urge the movable jaw 55 of the clamp or vise 53 (counterclockwise, Fig. 7) away from the stationary jaw 54 of the vise 53, and at this time the lug 41 on 10 the disc 40 engages in a notch of the Geneva gear 42 to advance the carrier 13 a step forward (right to left, Figs. 1, 5 and 6), from position "A" to position "B" (Fig. 6).

The cam surface 79 of the cam 61 then again 15 acts through the rocker arm 58-60, push rod 57, and arm 56 to move the clamping jaw 55 of the vise 53 into closed position and at this time the cam surface 83 of the cam 62 (Figs. 5 and 8) acts through the cam roller 95 and rocker arm 20 63 (Fig. 8) to raise the push rod 68, against the action of the resetting spring 99, whereupon a shoulder on the upper end portion of the push rod 68 engages the arm 84 of the feed roll 14 for the solder wire web 23; thus causing 25 the web-advancing rolls 24 to project the free end portion of the solder wire web 23 across the top of the particular cartridge fuse cap 18 carried by the fuse wire receptacle or carrier tube 14 which is at this time arranged in position "B" (Fig. 6). 30

When this operation takes place the action of the cam roller 93 riding off the cam surface 86 of the cam 62 (Fig. 5) causes the rocker arm 87 (Fig. 8) to move away from the push rod 73 (counterclockwise, Fig. 8), whereupon the tip 20 35 of the soldering iron 21 which is normally held in a raised position out of engagement with the web of solder wire 23 by engagement of the push rod 73 with the arm 71 of the soldering iron 21, is urged by the spring 89, (counterclockwise, Fig. 40 4) thereby causing the tip 20 of the soldering iron 21 to engage the free end portion of the solder wire web 23 and fuse said free end portion. This operation fuses the projecting upper end portion 26 of the fuse strip 22 to the cap 18 and deposits a small mass or globule 25 of solder upon the cap 18 to close the opening or hole 19 therein, as shown in Fig. 6 (position "B").

The cam surface 79 of the cam 61 then acts upon the rocker arm 58-60 to rock the latter 50 (counterclockwise, Fig. 7), whereupon the push rod 57 falls away from the arm 56 of the movable clamping jaw 55 (Fig. 7) and the latter pivots, under the action of the spring 90, away from the stationary jaw 54 of the vise 53. 55

At this time the lug 78 engages a notch in the Geneva gear 42 to advance the carrier 13 and the thus completed cartridge fuse unit 18-22 carried thereby from position "B" to position "C", (Fig. 6), whereupon the foregoing cycle of operations commences over again.

As the carrier 13 makes the turn around the sprocket 50 (Fig. 5), the stripper 78 engages the caps 18 of the fuse units 18-22 and pulls the latter out of the receptacle or carrier tubes 14, 65 whereupon the completed fuse units 18-22 drop by gravity (Fig. 1) into a suitable receptacle 21 provided therefor on the frame 12 of the machine.

The fuse units 18-22 may then be assembled 70 or converted into complete cartridge fuses either by suitable mechanical means (not shown) or manually, as desired.

While I have illustrated and described the preferred form of construction for carrying my in- 75

vention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters 10 Patent is:

1. A machine for making units for cartridge fuses, each of said units consisting of a strip of fuse metal having a cartridge fuse cap attached thereto, said machine comprising the combination of: an endless carrier; means for moving the said carrier in an intermittent step by step movement; a row of receptacle tubes mounted on said carrier and each having an open end; each of said receptacle tubes being adapted to have 15 arranged thereon a cartridge fuse cap having an opening or hole formed therein; means for supporting a web of fuse metal; means automatically feeding the free end portion of said fuse metal web successively through the said 20 openings or holes in said caps into said receptacle tubes; means automatically severing a strip from the free end portion of said fuse metal web after each insertion thereof so that a portion of said severed fuse strip projects outwardly of the 25 corresponding cartridge fuse cap through the opening or hole in the latter; means for supporting a web of fusible solder metal; means automatically feeding the free end portion of said solder metal web successively across each of said projecting fuse 30 strip portions; a soldering iron; and means automatically moving the said soldering iron into engagement with the said free end portion of said solder metal web so as to solder the said projecting portions of said fuse strips to said 35 caps.

2. A machine for making cartridge fuse units, comprising the combination of: a carrier; a row of receptacle tubes mounted on said carrier and each having an open end adapted to support an 40 apertured cartridge fuse cap; means for imparting an intermittent or step by step movement to said carrier; means for inserting the free end portion of a web of fuse metal successively through each of the said apertured caps carried 45 by said receptacle tubes and into the latter through the said open ends of the same, between movements of said carrier; means for severing a strip of fuse metal from the said free end portion of said web of fuse metal after each insertion of the 50 same; and means for soldering the said severed fuse strips and the said caps together after the aforementioned inserting and web-severing operations.

3. A machine for making cartridge fuse units, comprising the combination of: a carrier; receptacle tubes mounted on said carrier and each having an open end adapted to support an apertured cartridge fuse cap; means for inserting the free end portion of a web of fuse metal successively through each of the said apertured fuse caps carried by said receptacle tubes and into the latter through the said open ends of the same; means for severing a strip of fuse metal from the 10 free end portion of said web after each insertion thereof; and means for successively and automatically soldering the said severed fuse strips to the said cartridge fuse caps arranged upon said receptacle tubes after the aforementioned 15 inserting and web-severing operations.

4. A machine for making cartridge fuse units, comprising the combination of: a carrier; receptacle tubes mounted on said carrier and each having an open end adapted to support an apertured cartridge fuse cap; means for imparting an intermittent or step by step movement to said carrier; means for inserting the free end portion of a web of fuse metal successively through each of the said apertured caps and into the said 20 receptacle tubes through the said open ends of the same, between movements of said carrier; means for severing a strip of fuse metal from the said web after each insertion of the same; means for soldering the said severed fuse strips and the 25 said caps together after the aforementioned inserting and web-severing operations; and means for successively holding the said receptacle tubes and the said caps arranged thereon momentarily 30 in registration with the free end portion of the 35 said web of fuse metal during the aforesaid inserting and web-severing operations.

5. A machine for making cartridge fuse units comprising the combination of: a carrier; receptacle tubes mounted on said carrier and each having an open end adapted to support an apertured cartridge fuse cap; means for inserting the free end portion of a web of fuse metal successively through each of said apertured caps and into the said receptacle tubes through the said 40 open ends of the same; means for severing a strip of fuse metal from the free end portion of said web after each insertion thereof; means for successively and automatically soldering the said 45 severed fuse strips to the said cartridge fuse caps arranged upon said receptacle tubes after the aforementioned inserting and web-severing operations; and means for successively holding the said receptacle tubes and caps momentarily in 50 registration with the said free end portion of the 55 said web of fuse metal during the aforesaid inserting and web-severing operations.

HERBERT PERRY RENWICK.
